(57) **CLAIM**

The ornamental design for an electrical connector, as shown and described.

DESCRIPTION

FIG. 1 is a top plan view of an electrical connector; FIG. 2 is a front elevational view thereof; FIG. 3 is a bottom plan view thereof; FIG. 4 is a rear elevational view thereof; FIG. 5 is a right side elevational view thereof; FIG. 6 is a perspective view of the front and right side thereof; and, FIG. 7 is another perspective view of the front and right side thereof.

A left side elevational view of the electrical connector is omitted because it is presented symmetrical to the right side elevational view of FIG. 5.

A printed circuit board used with the electrical connector is drawn by dashed lines in FIG. 7 and forms no part of the claimed design.
